UNITED STATES PATENT OFFICE.

WILLIAM F. SHELLY, OF NEWCASTLE, INDIANA.

DOOR FOR MAIL-WAGONS.

SPECIFICATION forming part of Letters Patent No. 706,694, dated August 12, 1902.

Application filed May 16, 1902, Serial No. 107,592. (No model.)

To all whom it may concern:

Be it known that I, WILLIAM F. SHELLY, a citizen of the United States, residing at New-
castle, in the county of Henry and State of In-
diana, have invented certain new and useful
Improvements in Doors for Mail-Wagons, &c.; and I do declare the following to be a full,
clear, and exact description of the invention,
such as will enable others skilled in the art to
10 which it appertains to make and use the same.

My invention relates to an improvement in
doors for wagons, &c., for use more especially
in rural mail-wagons, and has for its object
to provide a door which when partially opened
15 forms an opening in connection with the door-
way of the wagon of sufficient size to allow
the mail-carrier to thrust his arm through to
deliver or collect mail, but at the same time
not large enough to expose his feet and limbs
20 in cold or stormy weather.

My invention consists in a door having one
of its corners cut out to form a recess and in
the features and combination of features, as
more fully hereinafter described and claimed.

25 The invention is illustrated in the accom-
panying drawings, in which—

Figure 1 is a side view in elevation of a
mail-wagon with my invention applied there-
to; Fig. 2, a detail side view of the door; Fig.
30 3, an edge view of the door and a portion of
the side of the wagon.

In the drawings, in which like letters of
reference denote like parts throughout the
several views, A represents a mail-wagon; B,
35 a doorway in the side of the same; C, a slid-
able door adapted to close said doorway and
having one of its corners, preferably the upper
left-hand corner, cut out to form a recess
D. A window D' of any suitable size is also
40 provided at the upper portion of the door.

E represents cleats fastened to the inside
of the door for the purpose of strengthening
and bracing the same.

F is a handle secured to the inside of the
45 door, by means of which the door is slid back-
ward and forward.

G represents rails or grooved strips secured
on the inside of the wagon, on which the door
is adapted to slide.

50 In Fig. 1 of the drawings the door is shown
in full lines in the position it assumes when
the carrier is delivering or collecting mail,

while the door is shown in dotted lines in its
normal or closed position. When the carrier
desires to get in or out of the wagon, he slides 55
the door until it leaves the doorway entirely
open. The space between the doorway and
the rear end of the wagon should be sufficient
to allow the door to be slid backward until it
clears the doorway. 60

When the carrier desires to deliver or col-
lect mail, he slides the door forward until the
recess in the corner thereof registers with the
upper left-hand corner of the doorway. Then
he thrusts his arm out of said recess and 65
without getting out of the wagon and without
exposing himself to the weather drops the
mail into a box or other receptacle or collects
it, as the case may be, and then closes the
door and drives to the next mail-box, where 70
the operation is repeated, and so on around
the entire route.

Instead of having the recess in the upper
left-hand corner of the door it may be in the
upper right-hand corner, and although only 75
one door and one recess are shown any num-
ber may be used.

I do not wish to be limited to the precise
construction as shown and described, as the
same may be changed somewhat without de- 80
parting from the spirit of my invention.

Having thus described my invention, what
I claim is—

1. A door having one of its corners cut out
to form a recess; in combination with a door- 85
way with which said recess is adapted to reg-
ister, substantially as described.

2. A wagon having a doorway, and a door
with one of its corners cut out to form a re-
cess, said recess adapted to register with said 90
doorway and form an opening into the in-
terior of the wagon when the door is moved in
one direction, and be covered or closed when
it is moved in the opposite direction, substan-
tially as described. 95

3. A door for a wagon having one of its cor-
ners cut out to form a recess, and the upper
portion of said door provided with a window
in combination with an opening in said wagon
with which said recess is adapted to register, 100
substantially as described.

4. A wagon having a doorway, and a slid-
able door with one of its corners cut out to
form a recess adapted to register with said

doorway and form an opening in connection therewith when slid in one direction, and when slid in the opposite direction to be covered by the side of the wagon, substantially as described.

5. A door having one of its corners cut out to form a recess and also having a window, in combination with a doorway with which

10
said window and recess are adapted to register, substantially as described.

In testimony whereof I affix my signature in the presence of two witnesses.

WILLIAM F. SHELLY.
